UNITED STATES PATENT OFFICE.

JOHN GEORGE BLASCHKE, OF HOT SPRINGS, ARKANSAS.

PERFUME VAPORIZER.

Application filed October 30, 1923. Serial No. 671,803.

To all whom it may concern:

Be it known that I, JOHN GEORGE BLASCHKE, a citizen of the United States, and a resident of Hot Springs, in the county of Garland and State of Arkansas, have invented certain new and useful Improvements in Perfume Vaporizers, of which the following is a specification.

This invention relates to a perfume vaporizer which is especially designed for use in theatres, public buildings or the like.

The object of the invention is to provide a vaporizer of this character which is attractive and ornamental in appearance so as to blend in with the decorative features of the building in which it is employed and which at the same time is effective to thoroughly disseminate the perfume, deodorant or other substance utilized.

Another important object of the invention resides in the provision of a device of this character and having the foregoing advantages and which is also equally well adapted to be mounted upon an upright or pendant electrical fixture such as are usually found in places where the device is used, the vaporizer employing electrical heating means whereby the electrical fixtures with which the device is associated are adapted to serve not only as supporting means therefor but also provide a source of current for the electric heating means of the vaporizer.

Another object is to provide a device of this character which is of simple, durable construction, easy and comparatively inexpensive to manufacture and operate.

Other objects and advantages of the invention reside in certain novel features of the construction, combination and arrangement of parts which will be hereinafter more fully described and particularly pointed out in the appended claims, reference being had to the accompanying drawings forming part of this specification, and in which:

Figure 1 is a perspective view illustrating one embodiment of the invention;

Figure 2 is a view thereof, partly in elevation, and partly in transverse vertical section;

Figure 3 is a view in side elevation, showing another embodiment of the invention; and

Figure 4 is a sectional view illustrating

the internal construction of the arrangement shown in Figure 3.

Referring to the drawings wherein for the sake of illustration is shown the preferred embodiments of the invention and more particularly to Figures 1 and 2 wherein the invention is shown constructed and adapted for use with pendant fixtures, the numeral 5 designates a supporting structure from which an electric fixture or socket 6 depends.

The vaporizer which constitutes the present invention is designated generally at 7 and is shown as comprising a hollow body or container 8 made up of an outer shell 9 of brass or other suitable metal crimped and formed to enlarge toward its upper end by a series of corrugations 10 of gradually increasing size. Preferably the shell 9 has integrally formed or otherwise secured to its lower end a pendant knob or ornament 11. The extreme upper edge of the metallic shell 9 is provided with an upstanding annular flange 12. An inner shell or liner 13 of plaster of Paris or other material impervious to liquid is snugly fitted within the metallic shell 9 and corresponds in shape thereto. The upper edge of the liner or inner shell 13 terminates immediately below the annular flange 12 of the metallic shell 9 and this upper edge of the liner 13 is formed with an inwardly extending horizontal marginal flange 14 providing a seat 15 for the lower flanged end 16 of a coupling ring 17 which rests on the seat 15 and which is suitably secured to the flange 12. The flange 12 may be beaded over the lower flanged end of the ring 17 or it may be welded, soldered or otherwise secured thereto.

A combined top and hanger 18 is provided and includes a hollow body 19 which is shaped to give it an ornamental appearance as shown in the drawings and which is preferably constructed of colored glass. The body 19 is provided with a series of outlets or holes 20 through which the vapors pass. The lower marginal edge of the glass body 19 terminates in an outwardly extending annular flange 21 which is engaged by a similar flange 22 formed on the upper edge of the coupling band 23 which is preferably constructed of

resilient metal and which fits over the coupling ring 17 carried by the body 9 of the container. This band 23 is provided with a number of nuts or bearings 24 in which

clamping screws 25 are threaded. These screws 25 engage the clamping ring 17 which if desired may be provided with seats or openings 26 for the screws 25. The upper 5 end of the glass cap 19 is provided with an opening 27 in which an internally threaded bearing bushing 28 is suitably secured. This bearing bushing 28 has threadedly connected thereto a screw plug 29 adapted to screw 10 into the socket 6 of the pendant electrical fixture. This plug 29 has its brass shell 30 extended below the lower end of the plug, as indicated at 31. The extension 31 of the shell of the plug 29 is corrugated or threaded 15 and engages the threaded internal wall of the bushing 28 and affords a socket for an electric lamp 32 which screws into the extension 31 and which is disposed within the top 18 and the container 8 for the purpose of 20 heating or vaporizing the perfume or substance placed in the container 8. Obviously the extension 31 may be releasably secured in the bushing 28 by any form of releasable fastening means and if found desirable the 25 inner wall or bore of the bushing may be made smooth, the extension being loosely fitted in the smooth bore and held therein by screws or the like in lieu of the arrangement shown. The illustrated arrangement is 30 however the preferred mode and has many advantages apparent to those skilled in the art. It is to be understood that the plug 29 is of standard and conventional construction except as to the provision of the extension 35 31 of its shell.

The form of the invention shown in Figures 3 and 4 is adapted for use with upright electric fixtures such for instance as designated at 35, the electric fixture embodying a socket 36. The vaporizer constituting the invention in this embodiment is designated generally at 37 and as before includes a container 38 made up of an outer metallic shell and an inner liner of plaster of Paris and shaped and ornamented in appearance as in the other embodiment. In lieu however of providing the pendant knob or ornament 10 the lower end of the container carries an electrical plug connection 45 39 adapted to screw into and electrically connect with the socket 36. From this electric plug 39 asbestos covered and insulated wires of electrical conductors 40 extend and are electrically connected with a socket 41 carried by the crown portion of a top or cap 42 provided for the container 38. This top 42 may be constructed of glass and of course is provided with suitable openings 43. It does not however function as a 50 hanger as in the previous embodiment and therefore it may simply rest on a flanged seat 44 provided therefor at the upper edge of the container although of course it may be suitably secured to the upper edge of 55 the container if found desirable. Any suit-

able securing means may be utilized and if desired the flange of the seat 44 may be made larger and provided with bearings for clamping screws or the top 42 may be threaded onto the flange of the seat 44. In 70 the socket 41 an electric lamp or heating element 45 is screwed and depends within the container 38 as in the other embodiment.

It is to be understood that in either embodiment of the invention the perfume is 75 placed within the container 18 or 38 as the case may be and this container being lined with plaster of Paris or other material impervious to liquid prevents escape or leakage of the substance. The provision of the 80 cap 18 in the one instance and 42 in the other protects the lamp as well as the substance within the container and prevents any appreciable amount of dust or other foreign matter from finding its way into the 85 container. When the vaporizer is in use the lamp or other heating element employed accelerates the vaporization or volatilization 90 of the perfume and brings about the thorough dissemination of the vapors which escape through the openings 20 or 43 as the case may be. Moreover the same means which provide for the electric connection of the lamp or heating element afford the support for the device and the device in either 95 99 embodiment and the entire device is so organized and constructed as to be ornamental in appearance and blend into the decorative features of the interior of the building while at the same time being durable, reliable and 100 safe in use and comparatively inexpensive to manufacture and operate.

In both embodiments of the invention the metallic shell providing the container is lined with an inner shell of plaster of Paris 105 or other similar substance which as before indicated is impervious to the liquid adapted to be placed within the container and this liner has the further property of not being corroded by the substance or being 110 chemically acted upon thereby. It also serves to insulate and protect the metallic shell from the injurious action of heat within the container.

I claim:

1. A vaporizer for use in theaters or the like, comprising a container for the substance to be vaporized, said container comprising a metallic shell adapted to be suitably ornamented, and a heat insulating and non-corrosive liner for the shell, said liner also being impervious to liquid.

2. A vaporizer for use in theaters or the like comprising a container for the substance to be vaporized, said container comprising a metallic shell adapted to be suitably ornamented, and a liner of plaster of Paris for the metallic shell.

3. A vaporizer for use in theaters or the like comprising a container for the sub-

stance to be vaporized, said container comprising a metallic shell adapted to be suitably ornamented, a heat insulating and non-corrosive liner for the shell, said liner also being impervious to liquid, said liner having a seat at its upper end, said shell having a flange extending above the seat, a per-

forated top, a coupling ring resting on said seat and secured to said flange, a coupling band having a flange engaged with the glass 10 top, the coupling band encircling the ring, and fastening means between the band and the ring.

JOHN GEORGE BLASCHKE.
